JULIUS H. SCHLAFLY, OF CANTON, OHIO.

MACHINE FOR THE MANUFACTURE OF FLUTED COLUMNS.

Application filed February 29, 1928. Serial No. 257,933.

This invention relates to the manufacture of fluted steel columns. These columns are made from a hollow steel pipe section, tapering throughout its length, and provided with ornamental flutes or corrugations. The object of the invention is to improve upon machinery for rolling the flutes in the column, the machine as shown herein being an improvement upon prior machines for this purpose in simplicity of construction and efficiency.

Other objects and advantages will be apparent to those skilled in this art and will appear as the description of the machine is given. It will be understood that exact conformity with the detailed construction as shown and described is not necessary, changes and modifications being possible without departing from the features of novelty and invention as set forth in the claims or within the scope of the invention as permitted by the prior art.

In the drawings, in which the preferred form of the invention is shown, together with certain modifications,

Fig. 1 is a side elevation of the machine, partly broken away, in its best form as known to me at the present time, showing a fluted column in place on the machine and showing several positions of the forming rolls at the various stages of the operation;

Fig. 2 is a section on the line 2-2 of Fig. 1;

Fig. 3 is a section on the line 3-3 of Fig. 1;

Fig. 4 is a section on the line 4-4 of Fig. 1;

Fig. 5 is a view of the preliminary forming rolls;

Fig. 6 is a similar view of the finishing rolls;

Fig. 7 is a section on the line 7-7 of Fig. 1, showing a modification of the mandrel elevating means;

Fig. 8 is a modification of the forming roll carrier; and

Fig. 9 is a still further modification.

The machine is designed for the purpose of rolling flutes in a tapered or conical sheet-metal pipe, which is placed in unfluted condition over a horizontal mandrel 2 ar-

ranged axially of the machine. The mandrel is formed with an elongated end portion 3 over which the unrolled tube is placed and with a tapering portion 4 upon which the column is rolled, this portion being provided with the requisite number of veins or ribs 5, the outer edges of which are reduced so as to secure a sharp edge at each high point on the finished pipe. The spaces between the ribs 5 permit the metal of the pipe to be formed as shown.

The base 6 of the mandrel is made cylindrical and is rotatably supported in a trunnion 7, collars 8 at either side of the trunnion fixing the mandrel in position. The trunnion is supported in bearings 9 in a base 10. At the rear of the trunnion on the shaft is secured a worm gear 12 which is engaged by a worm 13 by means of which the mandrel may be rotated, if such action is necessary in the operation of the machine. The mandrel is tilted in the bearings 9 by means of a large hand-operated set-screw 16 supported in a bracket 17 at the rear of the base 10 and bearing downwardly upon the rear end of the mandrel. The mandrel is supported at its forward end upon a concave pulley 18 mounted in a bracket 19 at the forward end of the machine.

To raise and lower the forward end of the mandrel by power, the device shown in Fig. 7 may be used. In this form the bracket 17 is provided with a pin 20 which slides in the bracket, being formed at its upper end with screw-threads engaging a nut 21 rotated by a bevel gear 22 which is operated by a bevel pinion 23 on the shaft of a motor 24.

Arranged about the mandrel as an axis are a plurality of spaced circular frames 25, to which are removably and replaceably attached a plurality of blocks 26, and to the blocks are secured a plurality of equally spaced parallel rails 28 which extend from the front end of the mandrel to a point at the rear of the working surface thereof and completely surround the mandrel in the form as shown in Figs. 1 and 2. These rails are preferably in the shape of I-beams, the inner flanges being designated at 29. The frames 25 and the rails are supported upon base members 30. The replaceable

blocks 26 enable the machine to be adjusted for different sizes of mandrels and for varying tapers, as will be understood from the subsequent description.

5. The formation of each of the rails may be seen in Fig. 1. Each rail has a horizontal portion or cam track 32 at the forward end and another horizontal portion or cam track 33 at the rear end. Immediately in 10 the rear of the portion 32 is an arched stretch 34 which is followed by an inwardly inclined or tapered stretch 35 which gradually approaches the mandrel and is substantially equivalent in degree of taper to the 15 taper of the mandrel, although oppositely placed. Over the portions or stretches 32 and 34 is located a supplementary flange 36 which parallels the lower flange 29 over that area.

20. Centrally located with respect to the framework and co-axial with the mandrel is a circular carriage 40 which surrounds the mandrel and is designed to move through its entire working surface. Extending radially from the carriage are a plurality of supporting brackets or forks 41, preferably four in number, which are placed at equal distances about the carriage and are arranged to slide along the rails to guide and 25 steady the carriage in its movement along the axis of the form. To the carriage, at opposite sides of the mandrel, are attached the ends of two parallel chains 44 which are supported upon a plurality of sprockets 45 30 to move in substantially rectangular paths, the upper runs of which are parallel to and located in the same plane as the mandrel. Sprockets 45^a are located at the bed plate 10 and are mounted upon a shaft 48, arranged to be driven in either direction 35 through clutch 49 operated by pulleys 50 driven by open and crossed belts 51.

Upon the carriage are located two sets of 40 rollers with their supporting levers, one set 45 comprising the preliminary forming rollers and the second set the finishing rollers. The preliminary forming rollers are designated at 55 and are in the form as shown in Fig. 5, although other forms of rollers may be 50 substituted, the shape of the flutes determining the shape of the rollers. The rollers completely surround the mandrel as shown. Each roller is mounted in a fork 56 which is secured to the inner end of a radially positioned lever 58. The attachment of the fork to the lower end of the lever is an adjustable attachment and is preferably secured by means of a bolt 59 passing through a slot in the fork and into the lever, a back- 55 ing screw 66 maintaining the fork in its proper position.

Each lever 58 is shown as an angular lever pivoted on lugs 60 formed on the carriage. The outer end of each is forked and spans 60 the respective rail 28, being provided with

rollers 61 which ride upon the flanges 29. It will be observed that there are eight of these levers in the set or gang and that eight of the rails are provided for the operation of these levers.

The finishing rollers are designated by the numeral 62 and are also arranged in a set of eight, which are placed to overlap or in staggered relation to the rollers 55 so that all of the flutes are properly and evenly 75 rolled. These rollers 62 are carried on levers 63 which are pivoted on brackets 64 extending rearwardly of the carriage, the mounting of the rollers being the same as the rollers 55. The levers 63 engage the 80 alternate rails 28 in the same manner as the levers 58, but trail those levers.

It is believed that the operation of the machine will be understood from the description which has been given. The carriage is moved forwardly to the dotted line position shown at the right in Fig. 1. In this position the rollers upon the two sets of levers are beneath the supplementary rail 36 and the rollers are moved outwardly in 90 position to clear the work. The forward end of the mandrel is raised by downward pressure upon its rear end, so that it is elevated above the roller 18. The tapered, unfluted column is then placed over the 95 mandrel and onto the working surface thereof, defined by the ribs 5. The carriage is now moved by the chains 44 to the left of Fig. 1 and the rollers engage the work, the second set trailing and finishing the operation started by the first set. As the rollers travel over the work, the pressure is applied thereto by the rails through the levers, and where the columns are of tapered formation, the rails are correspondingly 100 converged to maintain the desired fluting pressure. It will also be apparent that by adjusting the position of the rails, differently tapered columns can be accommodated and rolled in the machine.

As the carriage approaches the end of the work, the rollers pass over the end of the work to the dotted line position of Fig. 1. The weight of the levers may be so proportioned that they will maintain the position 115 shown in that portion of the view. The mandrel may then be elevated and the finished column withdrawn. Suitable stripping mechanism may be incorporated with the mandrel, such mechanism not being 120 shown herein. If it is desired to repeat the operation, the mandrel may be rotated between operations of the carriage.

In order to facilitate the withdrawal of the carriage and its forming rollers, the 125 modification may be adopted as shown in Fig. 8, in which a lever carries at its lower end a hinged arm 70 which contacts at one side with a stop 71. In moving toward the left in the fluting operation, the arm 70 re- 130

mains in vertical position against the stop. In moving toward the right at the end of the fluting operation, the arm may swing outwardly, clearing the work.

5 To reduce the number of levers and rails, an arrangement may be devised by which a single pivoted arm supports rollers on opposite sides of the mandrel. A device for this purpose is shown in Fig. 9, in which the carriage 75 is formed with brackets 76, in the outer end of each of which is pivoted a lever 77, one side of which carries the roller 78 which rides over the rail 28. The outer ends of the lever 77 are slotted and 10 are connected by pins to vertically moving arms 79 and 80, the former carrying rollers to operate on the side of the form adjacent the rail 28 and the latter being offset midway of its length and carrying rollers to 15 operate on the opposite side of the form. In this manner the parts of the machine can be reduced in number. If desired, the arms 80 can also be brought to a position beneath the arms 79 as shown in dotted lines in Fig. 20 25 9, thus equalizing the pressure upon opposite sides of the mandrel. In this modification, the roller 78 fits the rail 28 more closely than in the preferred form so that the pressure in opposite directions will be 30 properly applied.

It will have been noted that a simple and efficient column rolling machine has been developed, and it will be understood that modifications and variations may be made 35 within the scope of the invention as set forth in the claims. The movement of the carriage with respect to the mandrel is relative only.

What is claimed is:

- 40 1. In a machine for fluting tapering metal columns, a mandrel, a carriage movable longitudinally of the mandrel, a rail extending in the general direction of the mandrel, a lever pivoted on the carriage, a fluting element carried upon the lever, and a roller carried on the lever and moving over the rail, the pressure upon the element being applied by the rail through the direct contact of the pivoted lever with the rail.
- 45 2. In a machine for fluting tapered metal columns, a tapering mandrel, a carriage movable longitudinally of the mandrel, a rail extending longitudinally of the mandrel and converging towards the larger end of the mandrel, a pivoted lever on the carriage, and a fluting element carried on one end of the lever, the other end of the lever being movable over the rail with the movement of the carriage.
- 50 3. In a machine for fluting tapered metal columns, a tapering mandrel, a carriage movable longitudinally of the mandrel, a rail extending longitudinally of the mandrel and converging therewith, a pivoted lever on the carriage, a fluting roller on one

end of the lever, and a roller on the opposite end of the lever bearing on the rail, the pressure on the fluting roller through the lever being applied by the contact of the roller on the rail.

4. In a fluting machine, a mandrel, a carriage movable longitudinally of the mandrel, a rail extending longitudinally of the mandrel, a pivoted lever on the carriage, and a fluting element on one end of the lever, the opposite end of the lever bearing directly against the rail to apply pressure to the fluting element through the lever.

5. In a fluting machine, a mandrel, a carriage movable relatively to the mandrel, a pivoted lever on the carriage, a fluting element on one end of the lever, and means to apply pressure to the fluting element through the lever during the relative movement of the mandrel and the carriage.

6. In a fluting machine, a mandrel, a carriage movable longitudinally of the mandrel, a plurality of levers of the first class pivoted on the carriage, fluting rollers carried on one end of the several levers, said rollers completely surrounding the mandrel, and means to apply pressure to the fluting rollers through the levers during their travel over the mandrel, said means comprising guide rollers on the opposite ends of said levers and rails over which said guide rollers move.

7. In a fluting machine, a mandrel, a carriage movable longitudinally of the mandrel, a group of fluting rollers arranged on the carriage about the mandrel, said rollers being supported on levers and completely enclosing the mandrel, means to move the carriage longitudinally of the mandrel, and means to apply pressure to the rollers through the levers as they travel along the mandrel, said rollers operating to flute the entire surface of the work at a single operation.

8. In a fluting machine, a mandrel, a carriage movable longitudinally of the mandrel, a group of fluting rollers arranged about the mandrel and completely enclosing the same, a second group of rollers also arranged about the mandrel and enclosing the same, and means to move the said groups simultaneously over the surface of the mandrel.

9. In a fluting machine, a mandrel, a carriage movable longitudinally of the mandrel, a group of fluting rollers arranged about the mandrel and completely enclosing the same, a second group of rollers also arranged about the mandrel and enclosing the same and spaced from the first group, and means to move the said groups simultaneously over the surface of the mandrel.

10. In a fluting machine, a mandrel, a carriage movable longitudinally of the mandrel, a group of fluting rollers arranged

about the mandrel and completely enclosing the same, a second group of rollers also arranged about the mandrel and enclosing the same and spaced from the first group and arranged in staggered relation thereto, and means to move the said groups simultaneously over the surface of the mandrel.

11. In a fluting machine, a mandrel, a carriage movable longitudinally of the mandrel, a group of levers pivotally mounted on the carriage and arranged radially of the mandrel, a secondary group of levers also pivotally mounted on the carriage and arranged radially of the mandrel, fluting rollers carried on the inner ends of said levers, rails arranged longitudinally of the mandrel, and rollers on the outer ends of the levers movable over the rails.

12. In a fluting machine, a mandrel, a carriage movable longitudinally of the mandrel, a group of levers pivotally mounted on the carriage and arranged radially of the mandrel, a secondary group of levers also pivotally mounted on the carriage and arranged radially of the mandrel, fluting rollers carried on the inner ends of said levers, rails arranged longitudinally of the mandrel, and rollers on the outer ends of the levers movable over the rails, the fluting rollers and levers of one group being staggered with respect to the fluting rollers and levers of the other group.

13. In a fluting machine, a tapering mandrel, a circular carriage movable over the mandrel, a set of levers of the first class pivoted on the carriage and radially arranged with respect thereto, a plurality of rails equal to the number of levers, said rails converging toward the larger end of the mandrel, fluting rollers on the inner ends of said levers, and pressure rollers on the outer ends of said levers adapted to engage the rails to apply pressure to the fluting rollers through the levers.

14. In a fluting machine, a tapering mandrel, a circular carriage movable over the mandrel, a set of levers of the first class pivoted on the carriage and radially arranged with respect thereto, a plurality of rails equal to the number of levers, said rails converging toward the larger end of the mandrel, fluting rollers on the inner ends of said levers, pressure rollers on the outer ends of said levers adapted to engage the rails to apply pressure to the fluting rollers through the levers, and a secondary set of levers, fluting rollers and pressure rollers on the carriage and spaced from the first-named set.

15. In a fluting machine, a tapering mandrel, a circular carriage movable over the mandrel, a set of levers of the first class pivoted on the carriage and radially arranged with respect thereto, a plurality of rails equal to the number of levers, said rails

converging toward the larger end of the mandrel, fluting rollers on the inner ends of said levers, pressure rollers on the outer ends of said levers adapted to engage the rails to apply pressure to the fluting rollers through the levers, and a secondary set of levers, fluting rollers and pressure rollers on the carriage and spaced from the first-named set, the sets being arranged in staggered relation.

16. In a fluting machine, a mandrel pivotally mounted at one end, a support for the free end of the mandrel, means to rock the mandrel to elevate the free end thereof above the support, and fluting rollers movable longitudinally of the mandrel.

17. In a fluting machine, a mandrel, a carriage movable longitudinally of the mandrel, a set of forming rollers and a set of finishing rollers supported on the carriage, the said rollers operating simultaneously during movement of the carriage.

18. In a fluting machine, a mandrel, a carriage movable longitudinally of the mandrel, a set of forming rollers and a set of finishing rollers, pivoted levers for supporting each set on the carriage, and means for applying pressure to the rollers through the levers during travel of the rollers over the mandrel.

19. In a fluting machine, a mandrel, a carriage movable longitudinally of the mandrel, a set of forming rollers and a set of finishing rollers spaced therefrom, pivoted levers for supporting the several rollers of each set, and a rail for each lever over which it moves during the travel of the carriage.

20. In a fluting machine, a tapered mandrel, a carriage movable longitudinally of the mandrel, a set of forming rollers and a set of finishing rollers spaced therefrom, pivoted levers for supporting the several rollers of each set, and a rail for each lever over which it moves during the travel of the carriage, the rail converging toward the mandrel.

21. In a forming machine, a mandrel having a free end over which the work may be placed, a carriage movable longitudinally of the mandrel, forming rollers supported on the carriage, and means to spread the forming rollers when the carriage is at the free end of the mandrel.

22. In a forming machine, a mandrel, a carriage movable longitudinally of the mandrel, a set of forming rollers on the carriage movable over the mandrel and in contact with a portion thereof during the forming operation, and means to space the rollers outwardly of the mandrel after the completion of the forming operation.

23. In a forming machine, a mandrel, a carriage movable longitudinally of the mandrel, a set of forming rollers on the carriage movable over the mandrel and in contact

with a portion thereof during the forming operation, and means to space the rollers from the mandrel when they are inactive.

24. In a forming machine, a mandrel, a carriage movable longitudinally of the mandrel, a set of forming rollers on the carriage movable over the mandrel and in contact with a portion thereof during the forming operation, and means to space the rollers from the mandrel after the completion of the forming operation, said means comprising cam tracks and guiding rollers connected with the forming rollers and movable over the cam tracks.
- 15 25. In a forming machine, a mandrel, a carriage movable longitudinally of the mandrel, a set of forming rollers on the carriage movable over the mandrel and in contact with a portion thereof during the forming operation, and means to space the rollers from the mandrel when they are inactive, said means comprising cam tracks and guiding rollers connected with the forming rollers and movable over the cam tracks.
- 20 26. In a machine for fluting tapered metal columns, a tapering mandrel, a rail extending longitudinally of the mandrel and converging toward the larger end thereof, a carriage, the mandrel and the carriage being movable relatively to one another, a lever pivoted on the carriage, a forming roller on one end of the lever, and a guide roller on the other end of the lever and movable over the rail, said rail having a portion adapted to rock the lever and thereby move the forming roller radially outwardly of the mandrel at the end of its operation.
- 25

ing movable relatively to one another, a lever 30 pivoted on the carriage, a forming roller on one end of the lever, and a guide roller on the other end of the lever and movable over the rail.

27. In a machine for fluting tapered metal 35 columns, a tapering mandrel, a rail extending longitudinally of the mandrel and converging toward the larger end thereof, a carriage, the mandrel and the carriage being movable relatively to one another, a lever 40 pivoted on the carriage, a forming roller on one end of the lever, and a guide roller on the other end of the lever and movable over the rail, said rail having a portion adapted to move 45 the forming roller radially outwardly of the mandrel at the end of its operation.

28. In a machine for fluting metal columns, a mandrel, a carriage movable relatively to the mandrel, a lever pivoted on the 50 carriage, a guide rail, a forming roller on the lever, and a guide roller also mounted on the lever and movable over the guide rail, the pressure upon the forming roller being applied by the rail and the guide roller 55 through the lever.

JULIUS H. SCHLAFLY.
